Primary Examiner — Michelle E. Wilson(74) *Attorney, Agent, or Firm* — Studebaker & Brackett PC(57) **CLAIM**

The ornamental design for a clothes dryer, as shown and described.

DESCRIPTION

FIG. 1 is a front, top and right-side perspective view of a clothes dryer showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof;

FIG. 8 is a cross-sectional view taken along line 8-8 in FIG. 2, in which the internal mechanism is omitted;

FIG. 9 is a cross-sectional view taken along line 9-9 in FIG. 2, in which the internal mechanism is omitted;

FIG. 10 is a cross-sectional view taken along line 10-10 in FIG. 2, in which the internal mechanism is omitted; and,

FIG. 11 is an in-use, right-side view thereof.

The broken lines shown represent unclaimed subject matter of the clothes dryer and form no part of the claimed design. The clothes dryer has a first air outlet for supplying ordinary-temperature air and a second air outlet for supplying warm air.
